Inventor,
Fred Chevalier, by
G. C. Kennedy,
Attorney.

UNITED STATES PATENT OFFICE.

FRED CHEVALIER, OF WATERLOO, IOWA.

ANTIFRICTION-WHEEL.

1,293,707.

Specification of Letters Patent. Patented Feb. 11, 1919.

Application filed February 23, 1918. Serial No. 218,696.

To all whom it may concern:

Be it known that I, FRED CHEVALIER, a citizen of the United States of America, and a resident of Waterloo, Blackhawk county,

5 Iowa, have invented certain new and useful Improvements in Antifriction-Wheels, of which the following is a specification.

My invention relates to improvements in anti-friction wheels, and particularly to car-10 wheels, and the object of my improvement is to furnish easily operated means for introducing the anti-friction balls into the raceway of the wheel parts, and constitutes an improvement on the anti-friction wheel 15 which was patented by me in the United States, Number 1,176,342, dated March 21, 1916.

This object I have accomplished by the means which are hereinafter described and 20 claimed, and which are illustrated in the accompanying drawings, in which Figure 1 is a cross-section of one half of a car-wheel containing my improved means for introducing anti-friction balls into the raceway 25 between the parts of the wheel; Fig. 2 is a fragmental side elevation of the same part of the wheel showing the closure-block in place; Fig. 3 is an elevation of the outer face of a wheel of the type mentioned, with 30 parts broken away to disclose the reentrant cavity or seat for said closure-block; Figs. 4 and 5 are perspective detail views of said closure-block, as seen from different sides, and Fig. 6 is a perspective view of the 35 special locking bolt employed to secure said closure-block removably in its seat.

Similar numerals of reference denote corresponding parts throughout the several views.

40 The numeral 3 denotes a solid center casting for the annular wheel-rim 4, mounted concentrically therein, said center and rim having annularly mated raceway grooves providing a ball raceway 5 to contain anti-friction balls 6, and the center 3 is fixedly mounted on the squared extremity 2 of a relatively fixed axle 1.

The center 3 has a sloping reentrant port or passage with a shallow curved bottom 50 groove 8 leading into the raceway 5 to guide the balls 6 to enter the raceway from without in succession. I have furnished a removable closure-block 13 to fill said reentrant seat 7, having an inclined inner face with 55 raised curved rib 14 to fit said seat and its groove 8 when the block is in place. The

opposite sides of the block 13 are flat and parallel so as to fit removably the like sides of said seat 7, so that the block can be placed in the seat or withdrawn therefrom 60 easily and without interference in any way.

The block has a transverse orifice 18 through which a liquid lubricant may be introduced, and also a transverse bolt-hole 19 registering with a like bolt-hole in the 65 center 3 to receive a fastening bolt 23 provided with a nut 25.

In order to lock the closure-block securely in place I have provided the following securing-means in addition to said bolt 23. 70 The opposite side-walls of the seat 7 have transverse rectangular grooves 12 positioned opposite like transverse rectangular grooves in the side-walls of said block 13 as shown at 16, which thus furnish a pair of rectangular seats for the squared shanks 21 of the bolts 20, the latter having securing nuts 24. The outer ends of said rectangular seats are 75 rectangularly widened at 17 in both the center 3 and the block 13, to admit the rectangularly widened heads 22 of the bolts 20 flush with the outer face of said center 3.

After balls 6 have been passed into the raceway by way of the reentrant passage 7, the block 13 is fitted into the said passage 85 flush with the outer face of said center 3, the bolts 23 and 20 fitted in their seats and secured by means of their respective nuts 25 and 24. It will be seen that the squared heads and shanks of the bolts 20 will lock 90 the block 13 in its seat against any movements relative to the center 3, under the jars of transit, and are easily placed or removed when desired. The top of the block 13 has a concave groove 15 forming part of said 95 raceway, and into which the inner end of the channel 18 for passage of lubricant opens.

To keep dust from entering the raceway, I provide arc-shaped bars 26 to cover the outwardly opening spaces between the center 3 and the rim 4, supported removably on carrier-bars 27, the latter secured removably to the center 3. It will be seen that when all said parts are assembled and secured in 105 the manner described, the wheel center being fixed has the rim 4 rotatable around it, and thus serves for means of transportation for a car or vehicle.

My improved type of anti-friction wheels 110 are not only adapted for use on railway cars, but are especially fitted for employment in

2
 trucks, hand or power actuated, various vehicles, and in other applications such as will be obvious to those skilled in the art. The engaging-means for the closure-block 5 may be modified in form and dimensions without departing from my invention.

Having described my invention, what I claim as new, and desire to secure by Letters Patent, is:

- 10 1. An anti-friction wheel, comprising a relatively fixed center body, an annular rim mounted rotatably therearound, said center body and rim having registering annular concentric raceways, anti-friction balls in said raceways, said center body having a re-entrant cavity leading into said raceway to conduct anti-friction balls thereto, a closure-block removably fitting said cavity, and means for detachably securing said block in said cavity, consisting of like angular recesses in opposed faces of the block and the cavity walls, and securing-means mounted in said recesses, to fit same and prevent shifting of the block while fastening it removably to said center body.
- 15 2. An anti-friction wheel, comprising a relatively fixed center body, an annular rim mounted rotatably therearound, said center body and rim having registering annular concentric raceways, anti-friction balls in said raceways, said center body having a reentrant cavity with sloping inner wall leading into said raceway to conduct anti-friction balls into the raceway, a closure-block removably fitting said cavity, said
- 20
- 25
- 30
- 35

block having in opposite side walls transverse rectangular grooves which are widened rectangularly at their outer ends, the adjacent side walls of said cavity having like grooves registering with the adjacent 40 grooves in the block, and bolts fitted removably in said grooves, having rectangular shanks and widened heads to fit the grooves, and cylindrical extremities, the center body having bolt-holes in which the cylindrical 45 parts of the bolts are seated, and means to fasten said bolts to the center body, the rectangular heads of the bolts being flush with the outer face of said block, and the outer face of said block being flush with the abutting outer face of said center body.

3. An anti-friction wheel, comprising a relatively fixed center body, a rim rotatable about said body, said body and rim having raceways, anti-friction bodies movably positioned in said raceways, said body having a recess leading slopingly into its raceway adapted to permit said anti-friction bodies to be passed therethrough into and out of said raceways after the rim is mounted on 60 said center body, a closure fitting said recess, movable into and out of same slopingly, said closure containing part of the raceway groove therein, and means for detachably interlocking said closure with said body 65 when seated in said recess.

Signed at Waterloo, Iowa, this 6th day of Feb., 1918.

FRED CHEVALIER.
